Primary Examiner — Rebecca Tsehay*(74) Attorney, Agent, or Firm* — Cooley LLP**(57) CLAIM**

The ornamental design for an electronic cigarette, as shown and described.

DESCRIPTION

FIG. 1 is a bottom perspective view of an electronic cigarette showing my new design;

FIG. 2 is a front elevational view thereof;

FIG. 3 is a back elevational view thereof;

FIG. 4 is a left elevational view thereof, the right side being a mirror image;

FIG. 5 is a top plan view thereof; and,

FIG. 6 is a bottom plan view thereof.

In the drawings, the broken lines depict portions of the electronic cigarette that form no part of the claimed design.
